UNITED STATES PATENT OFFICE.

ULYSSE DAUBRESSE, OF NOVINGER, MISSOURI.

MINER'S ACETYLENE-LAMP.

1,087,645.

Specification of Letters Patent.

Patented Feb. 17, 1914.

Application filed April 20, 1912. Serial No. 692,052.

To all whom it may concern:

Be it known that I, ULYSSE DAUBRESSE, a citizen of the United States, residing at Novinger, in the county of Adair and State 5 of Missouri, have invented certain new and useful Improvements in Miners' Acetylene-Lamps, of which the following is a specification.

This invention relates to improvements in 10 miners' lamps, and has particular reference to an acetylene lamp.

The principal object of the invention is to provide a lamp of this character having a novel means for evenly distributing the 15 water over the carbide, said means also serving to permit the downward passage of the water and the upward passage of the gas simultaneously.

Other objects and advantages will be apparent from the following description and with particular reference to the accompanying drawings.

In the drawings: Figure 1 is a top plan view of the lamp, Fig. 2 is a front elevation, 25 and Fig. 3 is a plan view of the device; the dome and parts carried thereby being removed.

Referring particularly to the drawings, 10 represents a receptacle which forms the carbide chamber, in which the gas is generated, said receptacle having an annular flange 11, and an upwardly extending exteriorly threaded portion 12, which threaded portion is adapted to receive the interiorly 15 threaded lower end of the upper or dome-shaped portion 13. This upper portion has a horizontal partition wall 14 which divides the said dome into the upper or water chamber 15, and the lower or gas chamber 16, the lower end of the dome having a flange 17 which engages a rubber gasket 18 disposed between it and the flange 11 on the carbide receptacle. In the top of the dome 20 is a filling opening 19 having a suitable closure 20 provided with a pair of downwardly extending wire fingers 21 having the lateral offset portions 22 on their ends, said wire fingers being normally spaced apart a distance greater than the diameter of the opening 19 so that the same have to be compressed for insertion therethrough, thus when the closure cap 20 is lifted from the opening, the offset portions 22 will engage below the opening 19 and hold the cap 25 adjacent the opening so that its loss is prevented. Extending vertically through the

water chamber at one side is a tube 23 having the lateral inlet opening 24 disposed within the water chamber, said tube extending below the partition 14 into the gas chamber. Located in this tube is a rod 25 formed between a piece of metal, circular in cross section, one side for a portion of its length near the lower end being flattened as at 26.

Normally the rod 25 is rotated to the position so that its rounded side is against the opening 24 thus preventing outflow of water from the water chamber, but when the rod is turned to present the flat side toward the opening, a passage is formed to allow water to pass down through the gas chamber toward the carbide chamber. An inverted cap member 27 is located in the upper portion of the carbide receptacle, the diameter of said cap member being slightly less than the diameter of the carbide chamber so that an annular space 28 is formed between said cap member and the wall of the carbide chamber. Secured to the periphery of the cap member 27 is a continuous strip 29 formed with a continuous series of vertically arranged waves or convolutions 30 so that vertical passages 31 are formed between the cap member and the said strip. The lower edge of said strip is adapted to rest on the upper edge of the end threaded portion of the carbide chamber and in such position that the water which flows down through the tube 23 will drop on to the upper edge of the carbide chamber and pass down into said chamber by means of the space 32, the generated gas escaping from the carbide chamber upwardly through the passages 31 into the gas chamber 16, from whence it escapes through the burner pipe 32 to the tip 33 where it burns, a suitable projecting flange 34 being secured to the dome 13 and surrounding the opening through which projects the burner tube 34.

In the use of the device, when the same is attached to the cap of the miner the movement of the miner will cause the water to run around on the upper edge of the carbide chamber and flow through the openings 32 into the carbide chamber, the gas flowing up through the openings 31 to the gas chamber. From this it will thus be seen that by reason of the movements of the miner, the lamp will be so agitated that the water will pass all around the upper ledge of the carbide chamber, and finally overflow into the openings 32.

What is claimed is:

1. A miner's acetylene lamp comprising a carbid chamber, a cover provided with an opening therein, a water chamber located above the carbid chamber and detachably secured thereto, said water chamber being so spaced above the carbid chamber as to form a gas chamber therebetween, a valve for controlling the outflow of water from the water chamber, a pipe leading from the gas chamber and having a burner tip, and an inverted cap member located in the opening of the cover of the carbid chamber, said cap member having a convoluted strip secured to its periphery, said strip resting on the cover to support said cap in such relation thereto that the vertical passages are formed to permit the downward flow of water to the carbid chamber, and the upward flow of gas to the gas chamber.
2. In an acetylene gas lamp for miners' use, a water chamber a carbid chamber, the

water and gas chambers having a communicating opening, a valve in the opening, a gas chamber, between the water and carbid chambers, and a partition member between the carbid and gas chambers, said member comprising an inverted cap member fitting loosely within the upper portion of the carbid chamber, and a transversely fluted strip secured to the periphery of the cap member, said strip resting on the upper edge of the partition in such position that water from the water chamber will flow downwardly between the flutes and the wall of the carbid chamber, and gas flow upwardly from the carbid chamber between the flutes and the periphery of the cap member.

In testimony whereof I affix my signature, in the presence of two witnesses.

ULYSSE DAUBRESSE.
